SIFT-PROOF PATCH VALVE FOR PLASTIC SHIPPING BAGS

John J. Quackenbush, Monroe, Conn., assignor to National Distillers and Chemical Corporation, New York, N.Y., a corporation of Virginia

Filed Feb. 21, 1966, Ser. No. 528,961
5 Claims. (Cl. 229—62.5)

This invention relates to filling valves for plastic bags, and more specifically relates to a novel external patch valve having a folded central portion which defines a barrier between the patch entrance and the bag entrance.

Many types of valve are well known for plastic bags which permit filling of the bag through a filling spout, with the valve sealing the bag opening when the spout is removed. A common type valve for this purpose uses a single or multiple sleeve arrangement which must be built into the interior of the bag. Such valves are expensive and difficult to produce. Moreover, the sleeve-type valve, as well as most of the other prior art valves, usually do not automatically form a good seal when the filling tube is removed. Those valves which are arranged to be self-sealing are commonly found to be "leaky," and are difficult to open.

A primary object of the present invention is to provide a novel and inexpensive valve for plastic shipping bags which is connected to the exterior of the bag and which defines an effective self-sealing channel into the interior of the bag and which provides easy access to the interior of the bag by a filling spout.

In accordance with the invention, one panel of the bag is provided with a conveniently located slit, and this slit is then covered by an exterior patch having a folded central section. The exterior patch is then sealed on three sides to the bag exterior and around the slit with the fourth side defining a spout opening leading to the slit opening in the bag. However, the folded section is positioned in the spout channel and in front of the slit, thereby to define a resilient, self-sealing closure in the spout channel to prevent "sifting" or leakage of the bag contents through the spout channel and to prevent the passage of moisture through the spout channel. Moreover, the expansion of the bag by its contents will tend to further compress the folded section within the spout channel to increase the effectiveness of the seal.

Therefore, an important object of this invention is to form an effective self-sealing valve by the use of a single sheet of plastic connected to the exterior of a bag.

Another object of this invention is to provide an inexpensive but extremely effective self-sealing valve for plastic bags.

These and other objects of this invention will become apparent from the following description when taken in connection with the drawings, in which:

FIGURE 1 is an exploded perspective view of a plastic bag and the single plastic sheet having a rolled section therein which is connected to the exterior of the bag to define a filling valve.

FIGURE 2 is a front view of the bag of FIGURE 1 with heat seal sections shown by double cross-hatching.

FIGURE 3 is a cross-section of FIGURE 2 taken across line 3—3 in FIGURE 2.

FIGURE 4 is a view of the right-hand side of FIGURE 2 and illustrates the spout channel opening.

FIGURE 5 is a cross-sectional view of FIGURE 2 taken across line 5—5 in FIGURE 2.

FIGURE 6 is similar to FIGURE 5 but shows the insertion of a filling spout through the spout channel and into the bag interior.

FIGURE 7 is a cross-sectional view of FIGURE 2 taken across line 7—7 in FIGURE 2.

Referring first to FIGURES 1, 2 and 3, there is illustrated a typical plastic bag having front and rear panels 20 and 21, respectively, which are connected across their bottom by a suitable heat seal 22. Such bags are commonly formed of blown plastic tubing which is cut to suitable length. However, the invention is applicable to any type of plastic bag structure, including gusseted bags which are formed in any desired manner.

Any convenient part of the bag at which it is desired to receive a filling spout is then provided with a slit, shown as slit 23, extending from the top of panel 20 and off-set from the side edge of the bag.

In accordance with the invention, a spout channel 24 (FIGURES 4, 5, 6 and 7), which is self-sealing and which leads to slit 23, is formed by a single plastic sheet or patch 25 which is connected to the exterior of panel 20 in a simple and inexpensive manner. Patch 25 can be of the same material as the bag and is preferably heat sealable to the bag panel material. Typically, the bag panels and patch 25 could be of polyethylene having a thickness of 10 mils. The sheet 25, in accordance with the invention, is provided with a fold or rolled section 26, as shown in FIGURES 1, 2, 5 and 6, which defines a resilient, self-sealing body extending across the spout channel 24, as will be more fully described.

Patch 25 is secured to panel 20 by plastic heat seals 26 and 27 where seal 26 is behind slit 23, while seal 27 extends along the bottom of patch 25. Note that other means of securing patch 25 to the exterior of panel 20 could also be used such as cementing, or the like. Thereafter, an upper heat seal 28 completely seals through both panels 20 and 21 and the top of patch 25 thereby to define channel 24 extending from slit 23, between the exterior surface of panel 20 and the interior surface of patch 25 to the open end of patch 25 at the right in FIGURE 2.

In accordance with the invention, the fold, or roll 26, which may be a partial convolution or one or more convolutions in the patch 25 transverse to the channel 24 is captured at its outer edges by heat seals 27 and 28 to prevent unrolling, whereby the rolled shape is retained and presses against the exterior surface of panel 20 within channel 24. This then defines a self-sealing closure for channel 24, which is further pressed closed when the bag is filled by the outward bulging of the bag panels 20 and 21.

In addition to forming an effective sealing barrier in channel 25, the novel patch valve also permits easy entrance to a filling spout, as shown in FIGURE 6, where the spout presses the roll section 26 outwardly and passes through slit 23. Note that the roll section 26 normally will press the end of channel 25 slightly open for such easy access. After the bag is filled, and the filling spout is withdrawn, channel 25 will be automatically resealed by the rolled or folded section 26, as shown in FIGURE 5.

Although this invention has been described with respect to its preferred embodiments, it should be understood that many variations and modifications will now be obvious to those skilled in the art, and it is preferred, therefore, that the scope of the invention be limited not by the specific disclosure herein, but only by the appended claims.

The embodiments of the invention in which an exclusive privilege or property is claimed are defined as follows:

1. A patch valve for a plastic bag, said plastic bag having front and rear panels joined together; said front panel having an opening therethrough; said patch valve comprising a single elongated sheet disposed on the exterior of said front panel and overlying said opening; said patch valve secured to said front panel along a line only partially enclosing said opening and defining a closed channel bounded by the exterior surface of said front

panel, the interior surface of said patch valve and said partially enclosed sealing line which extends from said opening to the region of said patch valve which is uncured to said exterior surface; said patch valve having a rolled section interposed between said opening and uncured region; said rolled section terminating at either end on said partially enclosed sealing line.

2. The device as set forth in claim 1 wherein said patch valve is of thermoplastic material; said partially enclosed line of securement comprised of a heat seal.

3. The device as set forth in claim 2 wherein said opening comprises a slit in said front panel.

4. The device as set forth in claim 3 wherein said slit extends from the top of said front panel parallel to the side edges of said bag.

5. The device as set forth in claim 4 wherein said line of securement comprises first, second and third heat seals; said first heat seal extending across the top of said bag and sealing said front and rear panels and the top of said patch valve together; said second heat seal extending parallel to said slit and spaced laterally to one side of said

slit and sealing one side of said patch valve to said front panel; said third heat seal extending perpendicular to said slit and crossing the bottom of said slit and sealing the bottom of said patch valve to said front panel; said 5 rolled section extending parallel to said slit and spaced laterally to the opposite side of said slit; said first and third heat seals, respectively, extending across the opposite ends of said rolled section and securing said ends to said front panel.
